UNITED STATES PATENT OFFICE.

JOHN H. AHLGREN, OF LOS ANGELES, CALIFORNIA.

MASSAGE APPARATUS.

Application filed May 13, 1925. Serial No. 29,977.

This invention relates to massaging apparatus, and is more particularly directed to an apparatus for use in massaging the skin and flesh of the body to reduce the flesh from the body and give to the skin a more healthy and pleasing appearance.

Many types of massaging apparatus have been developed and are now in use. These apparatuses are for the most part of the cup or vacuum type employing a rotary motion for the reduction of the flesh and treatment of the skin. There are also many massaging apparatus employing a pounding or hammering stroke. I have discovered that a short, rapid, oscillatory stroke is extremely efficient for such use, and that the same will, in most cases, more rapidly reduce flesh from the body and is more beneficial in the treatment of the skin of the body. I have also discovered that, according to the individual treated, the rapidity and severeness of the oscillation or oscillatory treatment should be regulated. Some individuals under some conditions are able to stand a more severe treatment than others, and the most beneficial treatment in many cases is dependent upon the rate, length of stroke and severity of my oscillatory treatment.

An object of my invention is to provide an apparatus for imparting a rapid, short oscillatory stroke to massaging members that are adapted to be engaged with the body.

Another object of my invention is to provide an apparatus in which a variable or adjustable oscillatory stroke may be imparted to massaging members.

Another object of my invention is to provide a complete, compact apparatus so constructed and assembled that the same occupies a minimum of space, and which may be contained within a small space so that the same will provide oscillatory apparatus which may be transported with ease.

Other objects and advantages of this invention will be apparent from the following detailed description of a preferred embodiment thereof, as illustrated in the accompanying drawings.

In the drawings:

Fig. 1 is a side elevation of a massaging apparatus embodying this invention, illustrating the cover provided therefor in dotted lines.

Fig. 2 is a front elevation illustrating the cover in dotted lines.

Fig. 3 is a reduced front elevation there-

of, illustrating the cover attached to the apparatus.

Fig. 4 is a top plan view thereof.

In the preferred embodiment of this invention illustrated in the accompanying drawings, 1 illustrates a base plate preferably of circular contour and to which plate a pair of standards 2 are secured by any suitable means, such as the screws 3. Secured to the upper end of the supports 2 is a cradle 4 to which cradle a motor 5 is secured, the motor 5 being preferably an electric motor of the alternating current type of such voltage and current requirement that the same may be connected to the ordinary 110 volt light circuit in a manner well understood through cable 6 and socket (not shown). The shaft 7 of the motor has a pinion 8, which pinion 8 meshes with a gear 9 mounted upon the drive shaft 10, the shaft 10 being rotatably supported in the members 11, which members 11 are secured to the standard 1.

The shaft 10 has a cam or eccentric surface 12 secured thereto or formed integral therewith. An eccentric yoke 13 completely surrounds the cam surface 12 and is connected to a rod 14, which rod 14 has an interior bore 15 formed therethrough into which bore 15 a pin 16 is screw threaded. The pin 16 oscillates through the enlarged bore 37 formed in the base plate 1. Secured to the pin 16 is a collar 17 which collar engages one end of a helical spring 18. The spring 18 is engaged at its opposite end by an annular flange 19 on the eccentric yoke 13. The spring 18 is compressed in position so that the same yieldably urges the pin 16 outward from the bore 15. The spring 18 is employed to lock the pin 16 in the proper adjusted position and prevents the same from turning to unscrew from the bore 15. The pin 16 is screw-threaded into a traveling block 20 which traveling block is guided in position between the posts 21, the block 20 being recessed at its end to approximate the curvature of the posts 21, which posts 21 are secured to the standard 1 as illustrated at 22. Links 23 are pivotally secured to the traveling block 20 as illustrated at 24 and are pivotally secured at their opposite ends to arms 25 as illustrated at 26, which arms 25 are pivotally mounted within forks 27, which forks 27 are secured to the standard 1 as illustrated at 28.

The pin 16 it will be seen is threaded at

each end, left hand threads 16^a being employed at the end that is threaded into the bore 15 and right hand threads 16^b being employed at the end that is screw threaded into the traveling block 20 although it is to be understood that the adjustment obtained by this right and left hand threading might equally well be obtained by the use of threads of different pitch.

18 The opposite ends of the arms 25 are provided with oscillatory members 29, which oscillatory members are preferably of cylindrical form, or rather present a curved massaging surface 30. The members 29 are removably secured to the arms 25 in any suitable manner, such as illustrated by the screws 31, which are countersunk in the surface of the members 29. The pin 16 is provided with a head 32 to permit easy manipulation thereof. The cover 33 is provided for covering the motor 5 and gears 8 and 9, and is of the same contour as the standard 1 and is preferably secured to its periphery by means of screws 34.

19 The cover 33 is provided with ornamental handles 35 by means of which the apparatus is manipulated. The upper portion of the cover 33 is perforated as illustrated at 36 to permit the air to reach the motor 5 and to permit the exhaust from within the cover 33 of any gases formed by the motor 12.

20 The operation of my massaging apparatus is as follows:

21 The plug on the end of the cable 6 is inserted in any suitable electric light socket and the motor 5 thus set in operation. The shaft 10 is thereby driven through the gears 8 and 9 and the rotation of the shaft 10 operates through the cam surface 12 an eccentric yoke 13 to reciprocate the pin 16, which pin 16 is rapidly reciprocated in a vertical direction. The reciprocation of the pin 16 is translated through the links 23 and arms 25 to the massaging members 30 which are rapidly reciprocated through a short stroke, which stroke is determined by the cam surface 12 and the position to which traveling block 20 is regulated by means of the pin 16.

22 Having fully described a preferred embodiment of this invention, it will be obvious that the same may be varied in detail without departing from the spirit of the invention as set forth in the appended claims.

I claim:

23 1. In a device of the class described, the combination of a base, a motor, means for supporting the motor on the base, a shaft, means for driving the shaft from the motor, a pin passing through the base, means connected

24 to the shaft for reciprocating the said pin, 60 a traveling block screw-threaded to the pin, means supported by the base for guiding the traveling block, a pair of oscillatory members, arms secured to the oscillatory members and pivotally secured to the base, and a link 65 connecting each arm with the traveling block.

25 2. In a device of the class described, the combination of a base, a motor, means for supporting the motor on the base, a shaft, 70 means for driving the shaft from the motor, a pin passing through the base, means connected to the shaft for reciprocating the said pin, a traveling block screw-threaded to the pin, means supported by the base for guiding the traveling block, a pair of oscillatory members, arms secured to the oscillatory members and pivotally secured to the base, a link connecting each arm with the traveling block, a cover member removably secured to 75 the base, a plurality of air vents formed through the cover, and a pair of pivotally disposed handles secured to the cover.

26 3. In a device of the class described, the combination of a base, a motor, means for supporting the motor on the base, a shaft, 80 means for driving the shaft from the motor, a pin passing through the base, means connected to the shaft for reciprocating the said pin, a traveling block screw-threaded to the pin, means for adjusting the length of the pin connection between the said shaft and the said traveling block, means supported by the base for guiding the traveling block, a pair of oscillatory members, arms secured to 85 the oscillatory members and pivotally connected to the base, and a link connecting each arm with the traveling block.

27 4. In a device of the class described, the combination of a base, a motor, means for supporting the motor on the base, a shaft, 100 means mounted on the base for rotatably supporting the said shaft, means for driving the said shaft from the said motor, a pin passing through the base, means connected to the shaft for reciprocating the said pin, a traveling block secured to the said pin, means for adjusting the length of the pin connection between the shaft and the said traveling block, means supported by the base 105 for guiding the said traveling block, a pair of oscillating members, arms secured to the oscillating members and pivotally connected to the base, and a link connecting each arm with the traveling block.

28 Signed at Los Angeles, California, this 110

5th day of May 1925.

JOHN H. AHLGREN.
